(No Model.)

C. W. SIEMENS.
Electric Lamp.

No. 240,280.

Patented April 19, 1881.

UNITED STATES PATENT OFFICE.

CHARLES W. SIEMENS, OF WESTMINSTER, COUNTY OF MIDDLESEX,
ENGLAND.

ELECTRIC LAMP.

SPECIFICATION forming part of Letters Patent No. 240,280, dated April 19, 1881.

Application filed May 12, 1880. (No model.) Patented in England May 27, 1879.

To all whom it may concern:

Be it known that I, CHARLES WILLIAM SIEMENS, of Westminster, in the county of Middlesex, England, have invented a new and useful Improvement in Electric Lamps, (for which I have obtained a patent in Great Britain, No. 2,110, bearing date May 27, 1879,) of which the following is a specification.

According to one part of my present invention I cause the automatic advance or feed of a stick or tube of carbon forming the one pole of an electric lamp toward the other pole, to be determined by the heat produced by the electric arc. This heat, which is very intense at the extreme point of the carbon, in being transmitted longitudinally by conduction decreases proportionately to the distance from the point, so that at a certain distance the temperature is just sufficient to cause surface-combustion of the carbon to commence; and if at that point the advance of the carbon (which may be effected either by gravity or by spring power) be arrested by a stop formed of comparatively incombustible material which just touches the carbon rod or cylinder, the least wear of surface of the carbon round about the stop will permit the rod or cylinder to advance to the limit of the surface-combustion caused by the electric arc.

According to one arrangement for carrying out this method of regulating the advance of the carbons, I employ a construction of electric lamps having its carbons arranged horizontally, with means of advancing them as they are consumed and replacing them by fresh carbons, and of automatically regulating their distance, as I will describe, referring to the accompanying drawings.

Figure 1 is a vertical section of the lamp; and Figs. 2, 3, 4, and 5 are views, to an enlarged scale, of parts of one of the carbon-holders, hereinafter referred to.

A and B are the two carbons, which lie in guide-troughs M N or tubes open along their upper sides. These guide-troughs are jointed, respectively, to two forked levers, H and I. In the forks of these levers are mounted two barrels, a and b, containing volute springs. A cord

or flexible wire or strip is attached at its one end to each of these barrels, and its other end terminates in a hook, a' b', which is inserted in a countersunk hollow at the end of the carbon. The act of drawing out the cords or strings, unwinding them from the barrels for the purpose of inserting their hooks in the ends of the carbons, winds up the volute springs, which, by their effort to unwind, put tension on the cords or wires, tending to advance the carbons toward each other. Each of the carbons, near its point, is lightly clamped between two stationary chisel-edges, c' c', projecting down from a top piece covering the front part of the guide-trough, and a chisel-edge, c, below the carbon and nearer to its point than the edges c' c'. The construction of these parts will be understood by reference to Fig. 2, which is a transverse section on line X X of Fig. 1; Fig. 3, which is a part longitudinal section on the diagonal line Y Y of Fig. 2; Fig. 4, which is a transverse section on Z Z of Fig. 3, and Fig. 5, which is a plan, looking upward, of the upper edges, c' c', against which the carbon bears, and which, as shown, have diagonal serrations.

The edge c is formed on the end of a lever adjustable by a setting-screw, c², as shown applied to the carbon A in Fig. 1; or, instead of a chisel-edge, c, on a lever, the point of a screw, c³, may be employed, as shown applied to the carbon B in Fig. 1. By means of the screw c² or c³ the pressure on the carbon is adjusted so as to clamp it between the edge c or point c³ and the edges c' c' with sufficient firmness to prevent it from being pushed forward by the force of the spring. As the front end of the carbon becomes, by wasting, thinned round about the point where the edge c or point c³ bears against it, the clamping-force becomes sufficiently diminished by the crumbling away of the small portion of carbon on which the edge or point bears, thus permitting the spring to advance the carbon until a thicker part comes between the clamping-edges. When the carbons, as they are consumed, are thus advanced some distance along their respective guide-troughs, fresh carbons can be added to

them. These fresh carbons are made with points coned to enter the countersunk ends of the carbons already in the lamp, and before they are introduced their points are moistened 5 with a little sirup or caoutchouc solution, which, as the junction approaches the voltaic arc, becomes carbonized by the heat, thus rendering the new carbon continuous with the residue of the old carbon.

10 Over the carbon points is fixed a reflector, R, which, while it reflects downward the light of the voltaic arc, also protects from its heat the regulating apparatus above.

Under the carbons is a hemispherical bowl, 15 O, of frosted glass or enamel, to diffuse the light and reduce its intensity, as well as to receive such particles as may sparkle off the carbons. The bowl O may be inclosed within a wire-netting, o, to support it, and in case of its 20 fracture to prevent the fragments from falling.

The carbon-holders M N, besides being suspended by the levers H and I, rest also on non-conducting rollers m n, so that they are free to be moved to and fro horizontally.

25 The automatic regulation of the distance of the carbon points is effected in the following manner:

T is a rod guided to slide vertically up and down. A collar, S, screwed on this rod rests on 30 non-conducting rollers h i mounted on the arms of the bent levers H and I, the opposite arms of which carry counter-weights. The collar S carries an iron tube, D, which is free to move up or down within a solenoid coil, E, consisting 35 of a number of convolutions of fine wire, offering a high electrical resistance. The rod T has on it a piston, P, fitted to work in a cylinder having one or more small holes through its cover, and on the top of the rod is a cup, 40 Q, which can be charged with shot or other weight, so as to adjust the load on the rod T.

L L' are the line-wires conveying electricity to and from the lamp. L is connected, through a flexible metal strip, l, to the one carbon-holder, 45 M, and L' is in like manner connected, through a strip, l', to the other carbon-holder, N. L and L' are also connected together, through the coil of E, by the wires l l'. When there is no supply of electricity to the lamp the rod 50 T, with the weights upon it bearing down the arms of the levers H and I, separates the carbon points. If, now, the lamp be put in circuit, the electricity, finding no passage from the one carbon to the other, must pass entirely through the coil E. This causes the 55 iron core D to be attracted upward, relieving the rod T of a large portion of the weight bearing on it. The counter-weights of the levers H and I thereupon act so as to bring the 60 carbon points together, and the electricity passing through them kindles the lamp; but the quantity of electricity passing through the coil E being thus greatly reduced, the attraction of the core D becomes so far diminished 65 that its weight again acts so as to cause sepa-

ration of the carbons to the distance suitable for the voltaic arc. While the lamp continues in action the automatic regulation of the distance of the carbons is maintained in a similar manner. When the carbons are so distant as to offer great resistance to the passage of electricity the coil E becomes more strongly excited, attracting the core D with greater force, and so permitting the approach of the carbons. When the carbons are so near as to offer little resistance to the passage of electricity the coil E is less excited, attracting the core D with less force, and so causing separation of the carbons. The resistance of the air to the movement of the piston P damps the 70 vertical oscillations of the rod T and the parts connected with it, and the amount of damping may be adjusted by plugging some of the small holes in the cylinder-cover.

Having thus described the nature of my invention and the best means I know of putting it in practice, I wish it to be understood that I am aware a construction of lamp as described in the specification to Shepard's English Patent No. 2,368 of 1858, wherein it was 80 proposed to feed a carbon through a hole in a metal plate, which was intended to act as a stop, allowing the point of carbon to advance through the hole as it was consumed; but the said metal plate would have no such action, 85 as, owing to its great surface, it would conduct away the heat to such an extent as to prevent any wasting away or yielding of the carbon behind it, and consequently the carbon point originally protruded would merely burn away 90 up to near the plate, whereupon the electric arc would become extinguished, no feeding forward of the carbon being possible. I therefore in no way claim such an arrangement for feeding the carbon against a stop surrounding 95 the point; but

I claim—

1. An electric lamp having horizontal carbons pressed forward by springs against a clamping-pressure near their points, which 100 pressure yields as the carbons waste, allowing them to advance, the carbon-guides being connected to apparatus for automatically regulating their distance, substantially as herein described.

2. In an electric lamp, the conductors of the carbons and their guides, levers adapted to control the movement of the carbons, a solenoid coil of high resistance, its core and connections, as described, whereby said core, as 110 it is more or less attracted by the solenoid, bears with less or greater force on the carbon-controlling lever, substantially as described.

3. The combination of carbon-guide M or N, the volute spring a or b, and its cord or 120 wire, with hook a' or b', with the edges c' c', and the adjustable edge or point c or c³ in advance of the edges c' c', for the purpose of feeding onward the carbon A or B as it wastes, 125 substantially as herein described.

4. The combination of the high-resistance coil E, through which the conductors L L' are electrically connected with its core D, the levers H and I, and the carbon-guides M and N, for the purpose of automatically regulating the distance of the carbons, substantially as herein described.

5 In testimony whereof I have signed my name to this specification, in the presence of two

subscribing witnesses, this 22d day of April, 1880.

C. WILLIAM SIEMENS.
